UNITED STATES PATENT OFFICE.

JACOB F. WOODYARD, OF PARKERSBURG, WEST VIRGINIA.

PROPELLER.

1,103,855.

Specification of Letters Patent. Patented July 14, 1914.

Application filed February 20, 1912, Serial No. 678,761. Renewed May 4, 1914. Serial No. 236,355.

To all whom it may concern:

Be it known that I, JACOB F. WOODYARD, a citizen of the United States, and a resident of Parkersburg, in the county of Wood 5 and State of West Virginia, have invented certain new and useful Improvements in Propellers; of which the following is a specification.

This invention is an improvement in propellers adapted for use in water or air as well as for embodiment in wind-mills and electric fans; and the invention consists in certain novel constructions and combinations of parts as will be hereinafter described and claimed.

In the drawings Figure 1 is a perspective view from the rear, of a propeller embodying my invention. Fig. 2 is a rear elevation of the propeller wheel, and Fig. 2^a is an end view of a propeller having a plurality of bands. Fig. 3 is a section on about line 3—3 of Fig. 2. Fig. 4 is a section on about line 4—4 of Fig. 2. Fig. 5 is a section through one of the buckets on about line 25 5—5 of Fig. 2.

In carrying out the invention, I employ a hub A and a band or bands B spaced from the hub and concentric therewith.

Blades C, C and D, D extend between the hub and band and are of the special construction more fully described hereinafter. At their rear edges the blades C and D terminate at their inner and outer ends in about the same plane and the rear edges of said blades C and D connect with the band B at the rear edge of the latter, such rear edge of the band B lying in approximately a flat plane. The blades C are relatively wider than the blades D and may for such reason be termed the main blades while the blades D may be termed the supplemental blades. The blades D are at their inner ends, of about one-half the width of the inner ends of the blades C, while at their outer 45 ends the blades D are also considerably narrower than the blades C although the blades D like the blades C gradually increase in width toward their outer ends. It will be noticed that both the blades C and D curve 50 longitudinally and laterally giving a straight line running quartering from the cutting edge of the blade, the band holding the water making it take the grade, thus causing a perfect end thrust and also causing 55 less slip than is ordinarily experienced. The

curve gives the cutting edge a rounded scooping shape taking on a greater volume of water or air, giving more force to the wheel and making the grade easier on the front half and heavier to the rear half.

On the outer side of the band B, I provide buckets E which incline rearwardly from their front ends E' toward their rear ends E² and these buckets at their outer edges E³ gradually widen toward the center or toward a point midway between the ends E' and E² as best shown in Fig. 1 of the drawings. By thus widening the bucket midway between its ends, the lips so formed at E³ will operate to catch more water from the outside as the wheel revolves, thus giving greater power or end thrust to the wheel. The buckets E are in cross-section curved practically uniform from end to end and gather the water with a drawing cutting edge at their front ends. The lip E³, as the wheel revolves, gathers the water into the buckets by the draw or shearing cut of lip E³ as shown in Fig. 1.

It will be noticed especially from a comparison of Figs. 2 and 5 that the blades C at the front edges of their outer ends project slightly in advance of the front ends of the buckets E, the buckets E being thus set slightly back from the outer ends of the blades C for the purpose of catching any water that may be disturbed by the two wide or main blades C and the rim at the point where the said blades and band come together.

The band is narrow and cut away at the back of blades C and D and buckets E and is cut away at its front edge at F between the spaced apart buckets E and the two narrow or supplemental blades D it will be noticed, are set back from the front edge of the band, see Fig. 3. This cutting away of the band at F and the setting back of the narrow blades provides for catching all the water at the front of the blades causing therefor a suction or draw which with the narrow blades makes a better clearance and forces the water to the rear increasing the thrust of the wheel.

Manifestly the wheel may be used as a surface propeller when twin wheels are used working reversely, or as submerged twin wheels.

In large wheels two or three bands may be used as will be understood from Fig. 2^a. These bands besides holding the water and

making it take the grade, stiffen the blades preventing their quiver and unsteadiness, thereby giving better results.

I claim:

- 5 1. A wheel, substantially as herein described, comprising a hub, a band concentric with and spaced from the hub, a series of main blades between the hub and band and a series of supplemental blades between
- 10 the hub and band and alternating with the main blades, the supplemental blades being of less width than the main blades and terminating at their rear edges in approximately the same plane with the corresponding edges of the rear half of main blades, the front edges of the supplemental blades being set back relatively corresponding to the rear half of the main blades, a series of
- 15 buckets outside of the band and inclining from their front to their rear ends, the outer

edges of the said buckets being widened midway between their ends and the band being narrowed or cut away at its front edge between the adjacent buckets with the front edge of the main blades at the outer ends 25 thereof projecting in advance of their respective buckets, all substantially as and for the purposes set forth.

2. A wheel substantially as described, comprising a hub, a band, blades between 30 the hub and band and buckets on the outer side of the band, the blades at the outer ends of their front edges projecting in advance of their respective buckets, substantially as set forth.

JACOB F. WOODYARD.
